Inventor

JOHN SABOL.

By his Attorney

Irving L. McLathem

UNITED STATES PATENT OFFICE

JOHN SABOL, OF BROOKLYN, NEW YORK

SMOKE CONSUMER

Application filed August 31, 1928. Serial No. 303,253.

This invention relates to smoke consuming devices and in particular to one arranged for use in connection with steam generating boilers.

5 A particular object of the invention is to provide a smoke burner which gathers the heavy smoke that is passing up through the fire box and which returns the same to the boiler to be consumed.

10 In a great many neighborhoods, especially where soft coal is employed in boiler room operation, many complaints are made because an excess of smoke leaving the stack of the power plant, pollutes the air. Another 15 objection is that the efficiency of the boiler is lowered as an operating unit due to the waste of smoke which contains combustible material but which has not been consumed in the boiler.

A further object of my invention, therefore, 20 is to provide a steam operating smoke burning device which may be used in connection with any coal burning power plant where steam is available so that the smoke, upon leaving the boiler and passing into the fire 25 box, will be gathered and returned to the fire box for thorough consumption.

To enable others skilled in the art to fully 30 comprehend the underlying features of my invention that they may embody the same in the various modifications in structure and relation contemplated, a drawing depicting a preferred form has been annexed as a part of this disclosure and in such drawing, similar 35 reference characters denote corresponding parts throughout all the views, of which,

Figure 1 is a view in sectional elevation of a boiler unit to which my invention is applied.

Figure 2 is a section taken on the line 2—2 40 of Figure 1, and

Figure 3 is a section taken on the line 3—3 of Figure 2.

Referring to the drawings in detail, 5 indicates the boiler holding masonry or construction in which is supported the usual fire tube boiler 6, the tubes being indicated by the numeral 7 in Figure 2 and the end of the boiler 6 being arranged to support the smoke gathering hood 8 which, if desired, may extend entirely across the fire box 9 in which it is po-

sitioned, the hood being of any desired cross sectional shape but preferably semi-circular, as shown in Figure 3, so that it will have a high point in which will be accumulated the smoke as it comes out of the tube of the 55 boiler 6.

It is quite necessary in consuming the smoke that the same be returned to the fire box immediately over the grate and where the hottest flame is, and to this end, I have provided 60 a piece of pipe 10 having a flared intake mouth 11. This piece of pipe enters the hood 8 adjacent one end thereof and its depending portion 12 is arranged to hold the sleeve 13 to which is threaded the nipple 14 which abuts 65 against the end of the depending portion 12 of the pipe 10. This nipple is provided with an enlarged interior chamber 15, the exit from which is restricted as at 16 by reason of the fact that the interior walls are provided with a bevel 17. The end of the sleeve 13 is bevelled at 18 to substantially match the bevel 17 of the nipple 14 which may be adjusted so that its bevel 18 may approach or recede from the bevel 17, thus providing a restricted 70 passageway which acts to increase the velocity 75 of the steam passing therethrough, the steam being fed to a suitable pipe 19 whose end is threaded as at 20 into one side of the nipple 14. The steam line is provided with a suitable control valve 21 and the pipe, of course, leads from any suitable source of steam pressure so that it is assumed that the pressure is always in the line 20 and while the smoke 80 consuming device is in operation, is of course, 85 entering the chamber 15 and passing out through the restricted passageways 16 in the end thereof. The pressure in the enlarged chamber 15 causing the stem to have an increased velocity as it passes the end of the 90 sleeve 13, thus drawing in with it and intermingling, the smoke which has been drawn in through the flared intake mouth 11 of the pipe 10. The steam pressure, of course, forces the mixture through the pipe 22 out the flared 95 end 26 thereof and into the fire box 24 above the grate 25. The smoke therefore, passing through the boiler tubes 7, is caught under the hood 8 and due to the suction at the end 100 of the sleeve 13, is drawn out of the hood

through the pipe 10 through the sleeve 13 and, mixing with the steam coming in through the line 19 and through the nipple 14, is caused to move rapidly through the pipe 22, thus emerging from the flared mouth 26 thereof and directly into the fire box 24 for complete consumption.

It is evident that in a construction of this character, all the combustible material that has heretofore been lost by passage through the smoke box and into the stack is reburned in the fire box, thus saving the coal and consequently raising the efficiency of the boiler as an operating unit.

It is also evident that while I have shown a hood of elongated nature, the hood may be of any size or type desired, it being evident also that my improved smoke consumer or burning device may be applied to any power plant or boiler as set up and does not necessitate removal of the parts of the fire box or boiler for its insertion and use.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim.

Having thus described my invention what I claim as new and desire to secure by United States Letters Patent is:—

In a smoke consuming furnace having a smoke collecting hood positioned in a chimney, a pipe flared at one end thereof extending into the hood, a sleeve open at both ends thereof in the said pipe, a chambered coupling screw threadedly connected to the sleeve, a tapering end on the sleeve, a correspondingly tapered end in the coupling surrounding the tapered end of the sleeve, arranged to form between them a restricted passageway, a steam line connected to the coupling and an outlet pipe secured to the taper bearing end of the coupling provided with a flared end extending into a combustion chamber for the purpose specified.

In testimony whereof I affix my signature.
JOHN SABOL. [L. S.]
